CLARENCE A. BODDIE, OF PITTSBURGH, PENNSYLVANIA, ASSIGNOR TO WESTINGHOUSE ELECTRIC AND MANUFACTURING COMPANY, A CORPORATION OF PENNSYLVANIA.

REGULATOR FOR DYNAMO-ELECTRIC MACHINES.

1,284,573.

Specification of Letters Patent. Patented Nov. 12, 1918.

Application filed April 12, 1916. Serial No. 90,673.

To all whom it may concern:

Be it known that I, CLARENCE A. BODDIE, a citizen of the United States, and a resident of Pittsburgh, in the county Allegheny and State of Pennsylvania, have invented a new and useful Improvement in Regulators for Dynamo-Electric Machines, of which the following is a specification.

My invention relates to voltage and current regulators for dynamo-electric machines and particularly to regulators of the kind in which the regulation is effected by rapidly opening and closing a circuit in shunt to a resistor that is connected in series with the field-magnet winding of the dynamo-electric machine.

When voltage regulators have heretofore been employed in connection with excitors of large capacity and having large field currents, it has been customary to divide the regulating resistor that is connected in series with the field-magnet winding into a plurality of sections and to employ a corresponding number of relays for respectively controlling shunt circuits to the several sections. However, with the ever-increasing sizes of excitors and other dynamo-electric machines, it has recently been found that, when a certain field current is exceeded, no advantage is gained in employing more than two, or possibly three, relays in connection with a single resistor. This condition has served to limit the capacities of regulators, as heretofore constructed and arranged, and the present invention is intended to remove this limitation upon the field of application of regulators.

More specifically, the object of my invention is to provide means whereby an ordinary voltage regulator of the character above specified may be rendered capable of use in connection with an excitor or other dynamo-electric machine having a large exciting current without subjecting the contact members of the relays of the regulator to undue arcing and burning and to the resultant sticking or roughening and excessive wear.

My invention is illustrated in the accompanying drawing, the single figure of which diagrammatically illustrates an electrical system comprising distributing circuit conductors 1-2-3, a generator 4 having an armature 5 that is connected to the said con-

ductors, and a field magnet winding 6 that receives exciting current from an exciter 7 having an armature 8. The exciter 7 is provided with a field-magnet winding 9 in series with which are a plurality of parallel-connected resistors 10, 11 and 12, three of which are shown in the present instance but any suitable number of which may be employed, as desired. The circuits of the resistors 11 and 12 are adapted to be opened and closed by relays 13 and 14, respectively, that constitute parts of a voltage regulator and are provided with energizing windings 15 and 16 the circuits of which are controlled by a third relay 17 having an energizing winding 18 that is controlled by a pair of stationary and movable contact members 20 and 21, respectively, constituting parts of the main control element of the regulator. A suitable discharge resistor 22 and a condenser 23 are connected between the terminals of the relay 14 for the purpose of relieving the said contact members from undue arcing and burning.

The main control element of the regulator comprises also a bell-crank lever 24 that is pivoted at 25 to a stationary support, a lever 26 that is pivotally connected at 27 to the bell-crank lever 24 and is provided with an upwardly and laterally-extending arm 28 upon which the contact member 21 is mounted. The lever 24 is actuated by means of an electromagnet having an energizing winding 29 that receives energy from the circuit 1-2-3 through a transformer 30 and the degree of energization of which is controlled by means of a relay 31 that is adapted to open and close a circuit in shunt to a resistor 22 that is connected in series with the said winding. The relay 30 is provided with an energizing winding 33 that is connected in parallel with the energizing windings 15 and 16 of the relays 13 and 14 and is controlled by the relay 17. The lever 26 is actuated by an electromagnet having a winding 35 that is energized in proportion to the voltage of the circuit 1-2-3 and receives current therefrom through the transformer 30.

Since the regulator *per se* constitutes no part of the present invention, its operation will be described only in a very general way. The winding 35 serves to determine the position of the lever 26 in accordance with

the voltage of the circuit 1—2—8, while the winding 29, by reason of its being alternately fully and partially energized, serves to vibrate the contact member 21 into and out of engagement with the member 20. Engagement and disengagement of the contact members 20 and 21 cause the contact members of the relays 13, 14, 17 and 31 to vibrate into and out of engagement, the relays 13 and 14 opening and closing the circuits of the resistors 11 and 12, and thereby determining the effective value of the resistance in series with the field-magnet winding 9 of the exciter. The effective value of the current traversing the field-magnet winding 9 is thereby regulated in such a manner as to govern the exciter voltage to correct for any tendency of the generator voltage to vary.

20 When the contact members of the relays 13 and 14 are in engagement, the exciter field current divides substantially equally between the three paths through the resistors 10, 11 and 12, and, consequently, 25 when the contact members of the relays are separated, each relay is required to handle only a part of the total field current. Moreover, since the resistor 10 remains permanently in circuit with the field-magnet winding 9, the relays are not required to completely interrupt the circuit. The relay contact members are thus relieved from serious arcing and burning which might cause sticking and roughening and undue wear, and the 30 regulator is thereby adapted for use with excitors and other dynamo-electric machines having large field currents.

I claim as my invention:

1. The combination with a dynamo-electric machine having a field-magnet winding, of a plurality of parallel resistances connected in series with the said field-magnet winding, and a regulator having means that operate simultaneously to open and close the circuits of all but one of the said resistances, the circuit of the remaining resistance being unaffected by the regulator. 40
2. The combination with a dynamo-electric machine having a field-magnet winding, of a plurality of parallel resistances connected in series with the said field-magnet winding, relays included respectively in circuit with all but one of the said resistances, the remaining resistance being included permanently in circuit with the field magnet 50 winding and having such a value as to permit the flow of appreciable exciting current at all times, and means for governing the said relays. 55
3. The combination with a dynamo-electric machine having a field-magnet winding, of two parallel resistors connected in series with the said field-magnet winding, a relay included in circuit with one of said resistors, the remaining resistor being included permanently in circuit with said field-magnet winding and having such a value as to permit the flow of appreciable exciting current at all times, and means for governing the said relay. 60 65

In testimony whereof, I have hereunto subscribed my name this 31st day of March, 1916.

CLARENCE A. BODDIE.
